UNITED STATES PATENT OFFICE.

JOHN L. PREO AND ISABELLE HENNE, OF BROOKLYN, NEW YORK, ASSIGNEES TO
UNITED SHOE MACHINERY CORPORATION, OF PATERSON, NEW JERSEY, A CORPO-
RATION OF NEW JERSEY.

MACHINE FOR OPERATING ON THE SOLES OF SHOES.

Application filed February 18, 1922. Serial No. 537,394.

This invention relates to the manufacture of shoes and is illustrated herein as embodied in the heel-seat fitting machine arranged to trim surplus material from the peripheral 5 portions of the heel-seats of soles to fit the soles for the reception of heels.

In preparing shoes for the attachment of certain types of heels having concave attaching surfaces, of which wood heels are a typical example, it is necessary to trim away the peripheral portions of the heel-seats of the soles of the shoes in order that the heels may be attached to the shoes in such a manner that the edge of the sole is not visible between the heel and the shoe upper. At the same time the full thickness of the sole is desirable over the major portion of the heel-seat area to give strength to the shoe and to contribute to the foundation to which the heel is to be 10 nailed. It is highly desirable that this trimming operation, which is commonly spoken of as heel-seat fitting, be performed with precision and that the extent of the trimming operation conform with a considerable degree 15 of exactness to the configuration of the attaching surface of the heel to be attached to the shoe so that the edge of the heel will fit closely against the shoe upper both when the shoe is new and throughout its life and so as to facilitate a firm and solid attachment 20 of the heel to the shoe.

The heel-seat fitting operation has heretofore been performed for the most part by hand. As so performed, it requires both strength and skill and, at least in factories making high-grade or even fairly good medium grade shoes, it has therefore been a comparatively expensive operation.

It is accordingly an object of the present invention to provide a heel-seat fitting machine which will be simple and inexpensive to manufacture, rugged in construction and of such a nature that, with its assistance, the ordinary run of shoe factory help will be capable of doing a first-class heel-seat fitting job, and this without requiring the exercise of any great strength or unusual skill or care.

One of the more important problems to the solution of which the invention is directed is the organization of the machine to operate upon different sizes of shoes so as to fit the heel-seats of the shoes for the correspondingly different sizes of heels to be attached. A similar problem arises out of the varying

sizes and proportions of different styles of wood heels, regardless of the sizes of the shoes to which they are to be attached. With these problems in view, it is a further object of the invention to provide improved means for variably controlling a cutter arranged to trim surplus material from the peripheral portion of the heel-seat of a sole.

With these objects in view, a feature of the invention comprises a substantially horse-shoe-shaped guide surface conforming to the contour of the heel-seat portion of the sole of a shoe and arranged to control a suitable cutter movable peripherally of the heel-seat of a sole to trim surplus material therefrom. As illustrated herein, means is provided for varying the spread of the path of movement of the cutter by forming the guide surface on two relatively movable plates and moving these plates toward or from each other so as to vary the distance between the arms of the horseshoe in accordance with the size to which the heel-seat is to be trimmed.

In accordance with another feature of the invention, the illustrated machine is provided with a pair of crease plates pivotally adjustable about a point substantially in line with the back seam of the shoe to be operated upon and arranged to enter or be removed from the rand crease of the shoe to grip or to release the shoe, and a heel seat fitting cutter movable about the peripheral portion of the heel-seat of the sole of a shoe while said peripheral portion of the heel-seat is supported by the edges of said crease plates. Thus the shoe is held effectively regardless of its size as the surplus stock is trimmed from the heel seat of its sole.

It is a further object of the invention to provide a heel-seat fitting machine having improved means for making the heel breast receiving cut at the breast line of a sole. In the illustrated embodiment of the invention, this comprises a knife movable transversely of the sole and having a cutting edge inclined relatively to the surface of the sole and movable clear across the sole from one side to the other to make an inclined scarf or cut commencing toward the forward portion of the heel-seat and extending forwardly to the heel breast line and away from the tread surface of the sole, as illustrated in United States Letters Patent No. 1,527,963, granted Feb. 24, 1925, on an application filed

- as a division of the present application. The cut made by such a knife provides a flap of a substantial thickness where it joins the sole at about the heel breast line and tapering rearwardly to a thin edge. Such a cut is well adapted to receive the overhanging breast of a Louis heel, the flap overlying and ultimately being secured to the projecting portion of the breast of the heel.
- 10 Further to facilitate the performance of the heel-seat fitting operation upon shoes of different sizes and to which different styles of heels are to be attached, other features of the invention relate to the controlling of the forward extent of the path of movement of the trimming cutter and the controlling of the path of movement of the transversely moving knife which makes the heel breast receiving cut by connections controlled by a heel
- 15 such as is to be attached to the shoe. As illustrated this heel is placed between a fixed abutment and a movable gage member, the latter being brought into engagement with the heel and controlling by its location both the position of a stop which limits the forward movement of the trimming cutter and the position of the transversely moving knife.
- 20 Still another feature of the invention consists in an organization including a rotary cutter movable peripherally of the heel-seat of a sole to trim and bevel the sole for the reception of a wood heel and means for variably controlling the operation of said cutter to adapt it to operate upon soles having heel-
- 25 seats of varying sizes and shapes.

- With the above and other objects and features in view, the invention will now be described in connection with the accompanying drawings and pointed out in the claims.
- 30 It should be understood, however, that the illustrated machine is disclosed herein primarily for purposes of illustration and that various changes may be made in the organization of the machine within the scope of
- 35 the invention.

In the accompanying drawings forming a part hereof:

- Fig. 1 is a front elevation of one form of the machine;
- 50 Fig. 2 is a side elevation thereof;
- Fig. 3 is a plan view, on a larger scale, showing a shoe in the machine, the sliding table in its rearward position, the cutter in its initial position, and the templet adjusted for the minimum width of heel-seat;
- 55 Fig. 4 is a similar view, with portions broken away, the sliding table being shown in the forward position and the cutter being shown in full lines at the end of its travel and in dotted lines at an intermediate point in its travel;
- 60 Fig. 5 is a view similar to Fig. 4 but showing the cutter in its starting position and the templet adjusted for a wide heel-seat;
- 65 Fig. 6 is a horizontal section on the line

6-6 of Fig. 1, looking down on the shoe-holder and showing the trimming cutter in position to start its bevel cut;

Fig. 7 is a similar view with portions broken away to show parts beneath and illustrating the trimming cutter in its final position, having completed the bevel cut around the edge of the heel-seat portion of the sole;

Fig. 8 is a vertical transverse section on the line 8-8 of Fig. 3;

Fig. 9 is a vertical transverse section on the line 9-9 of Fig. 3, showing the transversely moving knife in the act of making the heel-breast receiving cut;

Fig. 10 is an enlarged fragmentary vertical transverse section showing the manner in which one of the crease plates of the shoe-holder engages the shoe;

Fig. 11 is a vertical longitudinal section on the line 11-11 of Fig. 3, showing the heel-breast receiving cut being formed by the transversely moving knife;

Fig. 12 is a sectional side elevation of the shoe-support on a large scale;

Fig. 13 is a front elevation thereof;

Fig. 14 is a sectional side elevation of the shoe-support on a smaller scale, showing the support tilted forward;

Fig. 15 is a sectional bottom plan, taken on the line 15-15 of Fig. 13;

Fig. 16 is an enlarged vertical section on the line 16-16 of Fig. 3;

Fig. 17 is an enlarged cross-section through the inner under portion of the knife-bar and the transversely moving knife;

Fig. 18 is a front elevation of another form of the machine;

Figs. 19 and 20 are fragmentary side elevations of this form of the machine, showing two positions of operating mechanism;

Fig. 21 is a fragmentary bottom plan view of a shoe in the condition in which it is when presented to the machine;

Fig. 22 is a corresponding view, showing the edge of the heel-seat trimmed and bevelled;

Fig. 23 is a bottom plan of the shoe, showing also the heel-breast receiving cut made by the transversely moving knife; and

Fig. 24 is a fragmentary side elevation of the shoe after both operations have been completed, indicating a heel in broken lines and the apron and tongue in readiness to be cemented against the breast of the heel.

Referring to Figs. 21 to 24, Fig. 21 shows the bottom of the rear part of a turned shoe in which the sole 1 has been split parallel with its heel-receiving face from the rear end to its shank portion, forming a flap or apron 2 which has been folded forward. This represents the shoe in readiness for the operation of the machine. The enlarged section of Fig. 10 illustrates the sole 1 with its channel 2^a and feather or extension 3, the shank or filler piece 4, the upper 5 with its lining

6, the counter or stiffener 7, and the stitching 8 by which the inturned edge of the upper and counter are fastened to the sole.

One of the functions of the machine of 5 this application is to trim and bevel the out-sole of a shoe around the sides and back of the heel-seat region, substantially as indicated by the dotted line α , in Fig. 10 thus exposing the margin of the heel-seat formed 10 by the turned-over surface 9 of the upper and to make preparation within this margin for the reception of the concave cup or attaching surface of the heel 10, (Fig. 24) which is to be applied. Fig. 22 illustrates 15 the beveled slope 11 which is to be formed on the trimmed heel-seat face of the sole as indicated at α in Fig. 10 and shows how the margin 9 or overlasted portion of the upper has been exposed so that the edge of 20 the heel may be fitted against it. Fig. 23 illustrates the result of the next operation 25 by which a scarf or forwardly-dipping cut 12 has been made transversely of the sole across the front of the heel-seat, resulting in 30 a tongue 13 of tapered thickness from its relatively thick root to its thin extremity. As seen in Fig. 24 this cut is formed at such 35 point that its base coincides with the position of the forward extremity of the attaching surface of the heel 10. The tongue extends entirely across the basal portion of the breast of the heel, and in this way, a 40 strong forward abutment is provided for the attachment of the heel; and when the tongue is cemented or otherwise secured 45 against the breast of the heel and the apron 2 cemented over the tongue and the remainder of the breast of the heel and trimmed, a double-breasted covering and joint is formed. The shoe just described is not claimed herein, since it forms the subject-matter of Letters Patent of the United States No. 1,527,963, granted Feb. 24, 1925, on an application filed as a division of this application.

The illustrated machine as shown particularly in Fig. 1, is provided with a frame including spaced side uprights 20 connected by suitable cross-members including an angle-bar 21 intermediate between their ends and a rod 22 toward the bottom. The uprights are further joined at the top by a bed 23, which bed is formed with a suitable recess 24, open at the front for the accommodation 55 of the shoe to be operated upon and its last. Bolted to the bed and forming a part thereof, is a bed-plate 25 having a corresponding recess 26. This bed-plate has a circular recess 27 in its top around the opening 26 as 60 shown in Figs. 9 and 11.

The circular wall of this recess, which is interrupted at the front to correspond with the entrance of the recess 24, 26, forms part of a bearing for the jaw members or crease plates 28, 28 of a shoe-holder. These jaw

members are of segmental form, their outer edges being formed as the segments of circles of the same radius as the circular bearing recess 27. Their inner shoe-engaging portions 29 are much reduced in thickness and taper 70 to comparatively thin edges, adapted to be introduced into the crease or crevice between the extension of the sole and the inturned portion 9 of the upper, as illustrated more particularly in Fig. 10. The upper surfaces of 75 these portions 29 are horizontal and flush with the horizontal upper surfaces of the forward body portions of the jaw members 28, and their bottom surfaces slope upwardly and inwardly to provide the desired taper. 80 The top surfaces of the rear portions of the bodies of the crease plates behind the shoulders 30 may, as shown in Fig. 11, be advantageously depressed somewhat, so as to afford a wider clearance between them and the cutter, hereinafter described, at the region where 85 close approach between the cutter and the top of the jaw members is unnecessary.

Curved grooves or recesses 31 are formed in the top of the crease plates 28 at their outer edges, and a retainer-plate 32, which is secured to the plate 28 and has a circular opening 33 of somewhat smaller diameter than the recess 27, overlies these recessed edges of 90 the jaw members and has a curved tongue 34 engaging the recesses for further bearing and 95 to hold the jaw members solidly at all times horizontal and against any undesired displacement. The engaging portions 29 of the crease plates 28 are curved to conform substantially to the sides and back of the shoe; that is to say, these edges form between them 100 an approximately horseshoe-shaped or U-shaped recess having an entrance at the front, sides which are comparatively straight or 105 slightly curved, and a curved back end. By oscillating the segments in opposite directions in the rim-bearing, the engaging portions 29 are caused laterally to approach and 110 recede in order to engage and grip the shoe in the manner indicated, thereby holding it firmly, with the sole exposed, for operation and to release the shoe when the work has been completed. This movement of the jaw 115 members is effected through forwardly diverging links 35 (Fig. 7), pivoted at their rear ends at a common point 36 to a lever 37 and passing forwardly in slots 38 in the bed-plate 25 and pivoted at 39 at their forward ends to the under parts of the crease plate, 120 members 28 to the rear of the center of the circular system. Thus crease plates 28 may be moved pivotally about a point substantially in line with the back seam of a shoe presented to the machine, the plates entering 125 and moving from the rand crease of the shoe to grip or to release the shoe. Moreover, the edges 29 of the crease plates will enter the rand crease and grip the shoe securely, irrespective of the size of the shoe.

The lever 37 is fulcrumed at 40 on a pin projecting from the rear part of the bed 23, and is actuated through a link 41 pivoted at its forward end to the free end of the lever 37 and at its rear end to the upwardly projecting arm of a bell-crank lever 42 (Fig. 11) fulcrumed at 43 on a bracket 44, secured to the bed 23. The forwardly projecting arm of this bell-crank is pivoted at 45 to the rear end of a lever 46, which is fulcrumed intermediate its ends at 47 on a bracket 48 secured to the bed, and at its forward end is provided with a handle 49 (Fig. 2) projecting at the front of the machine.

15 A strong spring 50 is interposed between an abutment 51 on the rear arm of the lever 46 and the under side of the bed 23. This spring acts upon the mechanism in a sense to cause the jaw members 28 to close upon 20 the shoe. Thus, the insertion of the entering jaws 29 of the jaw members in the rand crease of the shoe and the firm grip which they exert is produced through spring action which does not injure the shoe. The retraction of the 25 jaws is effected by manual operation upon the handle 49. Thus the shoe is centered and positioned, as well as held firmly in such manner as to present its sole for the action of the trimming and cutting mechanisms hereinafter to be described.

The machine is provided with a work support including a post 53 carrying at its upper end a tapered last pin 52 to receive the last carrying the shoe to be operated upon. Said 35 post at its lower portion passes through a hole in the forward part of a mounting block 54 (Figs. 12, 13 and 14), which is fixed on a transverse rock-shaft 55 extending between the side uprights of the frame. In the up- 40 right position the lower end of the post 53 rests upon one arm of a lever 56, which is fulcrumed between its ends on a pin 57 on the frame cross-member 21. The top flange 58 of this cross-member is slotted at 59 to 45 permit the post to pass through and to tilt in the manner illustrated in Fig. 14. A spring 60, connected at its upper end to a screw 61 on the post and at its lower end to a pin 62 projecting forwardly from the mounting- 50 block 54, tends to pull the shoe-support post downward in the mounting 54. Another spring 63, connected at its opposite ends to the pin 62 on the rockable mounting, and to a pin 64 on the frame member 21, tends to 55 rock the mounting and shoe-support forwardly. A stop pin 65 on the post limits the downward movement thereof in the mounting-block.

On the under part of the mounting-block 60 is a canting clutch plate 66, containing a clutch loop opening 67, slightly larger than the lower part of the post 53, which passes through it. The rear end of said clutch plate is confined with freedom for slight vertical angular movement between the under

side of the body of the mounting-block and a piece 68 bolted thereto and having a ledge 69. A pin 70 secured in the rear end of the clutch plate and projecting downward within a longitudinal slot 71 (Fig. 14) in said ledge prevents lateral displacement. A spring 72 interposed between the clutch plate 66 and the block 54 normally holds the clutch plate tilted slightly away from the mounting-block, so that the diagonally opposite front and rear 75 corners of its clutch loop opening 67 are in gripping relation to the post. The clutch therefore permits free upward movement of the shoe-support post but will hold it rigidly at any operative elevation against descent. 80

The relation between the clutch plate and the underlying flange 58 of the frame member 21 is such that when the shoe-holder is tilted forward for the removal of the treated shoe and the replacement of a fresh one, the 85 forward end of the clutch plate encounters the top of the flange 58, so that the spring 72 is compressed and the clutch plate brought flat against the bottom of the mounting-block 54, thereby releasing the grip and permitting the spring 60 to lower the shoe-support until the stop 65 strikes the top of the block 54. When the shoe is held in the embrace of the 90 jaws or crease plates 28 of the holder hereinbefore described, the spring 63 is powerless to rock the shoe-support forward out of the recess 24, 26 in the bed, the strength of the spring 50 which urges the jaws in the closing direction and the nature of the jaws and the 95 operating connections being such that the holding force is superior to the force of the spring 63 tending to rock the support. When, however, the holding jaws are opened, the spring 63 asserts itself to rock the support. The relations are such that its effect 100 overcomes the clutch spring 72, so that the clutch is thereby automatically released, permitting the automatic descent of the post 53 under the action of the spring 60. When the shoe-support tilts forwardly, the lower end 105 of the post 53 is carried rearward away from the lever 56, as seen in Fig. 14.

Means are provided for actuating the lever 56 to force the shoe-support and shoe upward against the under sides of the blade portions 29 of the crease plates 28 by spring action. In the particular construction illustrated in Figs. 1 and 2, a treadle lever 73 is fulcrumed on the tie-rod 22 and is connected by a stout spring 74, acting as a yielding 115 transmission element, with the other arm of the lever 56, the relations being such that depression of the treadle when the post 53 is in its vertical position over the lever 56 causes the post to be forced upward, but not by a rigid thrust which might injure the shoe or injure or displace the jaws 28 of the shoe-holder. Such upward pressure seats the last 120 firmly upon the last pin 52 and the shoulder at the base thereof, and presses the turned-in 125 130

portion of the upper close against the under sides of the edge 29 of the crease plates 28. The clutch 66 by gripping the post 53 against downward movement then preserves this adjustment, and insures solid support for the shoe while being worked upon. By virtue of the disconnection between the lever 56 and the lower end of the post 53, and the cooperation of the clutch with the post, the latter 10 remains elevated irrespective of whether the foot-pressure is maintained upon the treadle 73 or not. A light compression spring 200, acting upon the lever 56, is provided for the purpose of restoring it to normal position 15 with its arm which is beneath the shoe-support post lowered.

Secured to opposite sides of the bed 23, and rising therefrom (Fig. 8), are blocks 75 forming a further part of the frame of the machine. Horizontal longitudinal slide ledges 76 are formed on the upper inner portions of said blocks, and supported slidably upon these ledges and accurately guided between the side surfaces 77 is a table 78. The table 25 is further guided and held against upward displacement by retaining strips 79 fastened to the tops of the blocks and projecting inward to occupy rabbets in the top of the table.

The table 78 is constructed of upper and 30 lower plates 80, 81 secured together by screws 82. The opposing faces of the plates 80 and 81 form plane bearing surfaces, which are separated by spacer portions 83 at the sides so as to afford a flat guide pocket occupying 35 substantially the whole interior of the table.

The plates 80 and 81 of the table are formed with interior openings 84, 85, to permit the movement of a cutter-head 88, which in operation travels around the sides and 40 rear of the heel-seat. The lower opening 84 may be simply a large cavity, and may be open at the front, while the opening 85 in the upper plate is preferably of general horse-shoe form, corresponding roughly in 45 shape to a guide surface illustrated as a slot 86 of a templet 87 (Figs. 3, 4 and 5), which lies on top of the plate 81. The opening 85 is made in this form instead of like the opening 84 in order to leave ample bearing surfaces 50 for the sections of the templet to rest upon, and the opening is sufficiently larger and wider than the slot in the templet not to interfere with the movement of the cutter in any adjustment of the templet. A cutter- 55 head housing 89 projects downward through the opening 84 in the lower plate 80 of the slidtable table, with its lower end in proximity to the top of the crease plates 28 of the shoe-holder. A large plate illustrated as a 60 disk 90 is formed on or secured to this housing, and projects widely therefrom within the flat slide pocket in the interior of the table. The upper and lower surfaces of the disk 65 are plane bearing surfaces, and the disk is closely embraced by the enclosing station-

ary bearing surfaces of the plates 80, 81, so that the cutter-head is supported and solidly held against any deviation from the vertical while being free to move in all directions parallel with the surfaces of the table.

A bushing 91 fixed in the upper end of the housing 89 and forming part thereof projects upwardly through the opening 85 in the top plate 81, through the slot 86 in the templet 87 and through a circular hole intermediate between the ends of a lever 92, which lies flat upon the templet 87. A rotary cutter-shaft 93 passes vertically through the bushing 91 and through a vertical bearing in the body of the housing 89, and at its lower end bears a rotary beveled toothed cutter 94, the function of which is to trim and bevel the edges of the heel-seat portion of the sole. The cutter is supported so that its bottom is spaced at a minimum clearance from the forward portions of the holder jaw members 28 as shown in Figs. 9 and 11, and is sustained in this position against either upward or downward displacement by a collar 95 pinned to the shaft 93 and bearing on the top of the lever 92, and by a collar 96 on the lower part of this shaft bearing against an interior shoulder 97 in the lower part of the housing. The lower end of the housing, below this shoulder, is formed as an angular guard and presser-foot 98 encircling the cutter teeth and connected with the body of the housing by posts 99, the spaces between which permit the escape of the shavings.

The upper end of the shaft 93 is provided with a coupling socket 100 and screws 101 for connection with the terminal 102 of a flexible driving shaft, receiving its power from a suitable source. The driving shaft for the cutter, it will be observed, passes through the slot 86 of the templet, in which the upper end of the bushing or stem 91 of the cutter-head is accurately guided as shown in Fig. 4.

From the foregoing it will be perceived that the rotary cutter is supported with its axis of rotation perpendicular to the plane of the sole to be operated on in such manner as to be movable universally in directions parallel with said plane.

The templet 87 is of sectional construction, enabling it to be adjusted for shoes and heel-seats of different sizes. In the construction illustrated the templet is divided into two lateral sections 103, 104, the central meeting portions 105, 106 of which are of half thickness and overlap each other to form at all times a closed joint and a continuous path in the slot 86 for the stem of the cutter. See Figs. 3, 4 and 9. In their forward portions said sections 103, 104 contain approximately one-half each of the horse-shoe slotted guide 86, this guide consisting of two arms in the two sections and the curved connecting portion formed part in one section and part in the other. As seen in Fig. 4, for example,

the horseshoe guide is disposed with its arms pointing to the front and the curved connecting portion at the rear. The end of the slot in the section 104 is enlarged at the outer side 5 to form a lateral vestibule 107, and the opening 85 in the plate 81 beneath is correspondingly enlarged at this region. Before the cutter is brought into engagement with the shoe to be operated upon, bushing 91 is received 10 in this vestibule, and the cutter consequently is disposed somewhat to one side of the shoe-heel region when the table 78 is moved forward.

The templet sections 103, 104 have rearward 15 extensions 108, 109, which are pivoted to the top of the table on laterally spaced pivot pins 110, 111, the construction being such that when the sections pivot slightly in opposite directions upon these pins to vary the spread 20 of the slot 86 the relative movement of the sections of the slot 86 at the forward ends is substantially parallel. Equal movement of the sections of the templet is effected by a lever 112 (Fig. 3), which is pivoted at one end 25 113 to the top of the table and extends across the flat tops of the rearward extensions 108, 109, these sections being formed with inclined slots 114, 115 into which project pins 116, 117 on the lever. A handle 118 on the free end of the lever 112 enables it to be conveniently manipulated so as laterally to expand or contract the templet sections. In this way the templet is adjusted for any 30 width of heel-seat. When adjustment has been effected, the sections are locked by means 35 of a nut 119 on the upper end of a screw stud 120, which is fixed in the top of the table and projects upward through suitable enlarged openings in the templet sections and in the lever 112. Fig. 4 shows the templet sections 40 adjusted so as to lie close together for the minimum width of heel-seat, and Fig. 5 shows them slightly separated for substantially the maximum width of heel-seat.

The cutter-head is moved around in the horse-shoe slot 86 of the templet by means of a universal linkage comprising the lever or arm 92 heretofore referred to and another arm 121. The arm 92 carries the cutter-head 45 intermediate between its ends, and at one end is provided with a handle 122 and at the other end is pivoted at 123 to the arm 121. The two arms are in angular relation, and the rear end of the arm 121 swings on a relatively fixed pivot 124 on the rear portion of the slidtable 78. For added convenience in operation the arm 121 is preferably extended forward from the pivot 123, and is also provided with a handle 125 (Fig. 3), so that the operator can control the movement of the cutter by use of both hands.

From the foregoing it will be perceived that the slidtable 78 at the top of the machine carries the heel-seat trimming and beveling cutter, the means for solidly sup-

porting the same for universal two-dimensional movement over the shoe-holder, and the means for giding or directing the cutter and for effecting its movement.

At the time when a shoe to be operated upon is put in the machine and introduced into the holder by which it is positioned and gripped, the slidtable is in the rearward position and the stem of the cutter is in the vestibule 107 at the starting end of the slot 86 of the templet. When the shoe is in place the table is moved forward, carrying with it the cutter, which, however, does not at this time encounter the shoe, because of being offset to the side in the vestibule. A suitable stop, such as represented for example by projections 126, 127 on the fixed frame and table respectively (Fig. 11) limits the forward movement of the table to a definite position in which the slot of the templet is positioned 85 exactly over the position of the heel-seat region of the shoe as determined by the shoe-holder. The table is held forward during the trimming and beveling operation and is then moved backward.

Mechanism is provided for moving the table, which mechanism is advantageously combined or united with the mechanism for elevating the shoe support post 53. In the construction illustrated in Figs. 1 and 2 and 95 corresponding views, a link 128 is connected at its lower end to the treadle lever 73, before referred to, and extends upward through a slot in the bed 23 to a bell-crank 129, which is pivoted at 130 to the fixed frame. 100 See Fig. 11. One arm of this bell crank is pivoted at 131 to the upper end of link 128 and its other arm is pivoted at 132 to the rear end of the table by a pin-and-slot connection. Consequently, depression of the treadle 73 not only produces yielding upward pressure on the shoe-support through the spring 74, but also advances the table. Return movement of the table and restoration of the treadle 73 and the connected parts to normal position is effected by a spring 133.

The left-hand block 75 of the upper part of the fixed frame is formed with a horizontal longitudinal guide slot 134, in which a slide 135 is guided for adjustment forwardly or rearwardly, this slide having flanges 136 overlapping the outer and inner faces of the fixed block so as to prevent all lateral displacement. See Figs. 1, 2 and 9. The slide is adjustable by means of a screw 137 journaled and held against longitudinal movement in a plate 138 bolted to the front end of the fixed frame member and entering a screw-threaded bore 139 in the slide, the screw having a knurled head 140 on its front end for operation. The slide 135 has a bearing opening formed transversely through it, and in this a knife-bar 141 is solidly supported and guided for reciprocating movement trans-

versely of the machine and of the position of the heel-seat.

In order to insure efficacy of movement of the guide-bar and to take up any wear in the bearing, a shoe 142 is provided (Fig. 9), this shoe being an angular piece fitted to an inner corner of the guide opening in the slide so as to bear with one flange flat against the top of the knife-bar and with the other flange against the inner face of the slide. The latter flange is formed with a vertically-slotted hole 143 to receive the neck of a screw 144, which is screwed into the slide and retains the shoe by virtue of its enlarged head. A take-up screw 145 passes vertically downward from the top of the flange of the block to bear upon the lower flange of the shoe 142. The knife-bar is thrust inward by operating mechanism, including a treadle lever 146 fulcrumed on the tie-rod 22, a link 147 extending upward from the treadle lever, and a bell-crank 148 fulcrumed on a fixed bracket 149, one arm of said bell-crank being pivoted to the upper end of the link and the other arm having a pivotal connection with the outwardly projecting end of the knife-bar. The said connection is formed by a bifurcation 150 in the outer end of the knife-bar, and a pin 151 extending across the interior of this bifurcation and through a slot 152 in the upper end of the arm of the bell-crank. The bifurcation in the end of the knife-bar is sufficiently wider than the thickness of the arm of the bell-crank to allow for the range of the adjustment movement of the slide 135.

At its inner end the knife-bar carries a knife 153, the function of which is to make a forwardly declining cut extending across the front of the heel-seat region of the sole, thereby forming the tongue and heel abutment 13 which was described in the early part of the specification. This knife blade is secured by screws 154 to a downwardly and forwardly inclined face on a downward extension 155 from the lower rear portion of the knife-bar at the inner end of said bar. The blade projects forward from this extension and is set at a small angle to the horizontal, substantially as shown, dipping forwardly of the machine and transversely with respect to the direction of movement of the knife. The cutting edge of the knife is at its advancing end, that is to say the end which leads on the inward or cutting stroke of the knife-bar. It will be perceived, therefore, that when the knife-bar is forced inward, the knife will enter the sole at one side edge, and thence travel completely across through the leather of the sole to the opposite edge, forming a low-angle scarf cut which is straight from side to side and slants downward and forward from the top of the leather from a transverse line which is within the heel-seat region to a transverse line representing the bottom of the cut which is at the front of the

heel-seat region, the bottom of the cut being part way through the sole. By virtue of this cut a tongue of substantial length, decreasing gradually in thickness from its base to its tip, is formed and a low bevel is produced 70 across the front of the heel-seat, which is desirable as a preparation for the reception of the forward extension of the breast of the heel which is later to be applied.

The exact position forward or rearward 75 of the sole at which this cut is made is regulable by adjusting the slide 135 by the screw 137. This is of importance, since shoes of different sizes require different lengths of heel-seats. The adjustment slide 135 also 80 carries a bar 156 which projects inwardly and transversely of the machine. This bar has a straight rear face, which extends horizontally at right angles to the direction of movement of the slide 135 and lies in front of the 85 housing 89 of the rotary cutter. This bar is so positioned on the slide 135 with respect to the knife 153 as to constitute a forward gage for the rotary trimming cutter. Thus one and the same adjustment in respect to 90 length of heel-seat serves to determine the position of the heel-breast receiving cut and to determine the forward extent of the trimming cut.

When the table 78 is in its forward position the housing 89 of the rotary cutter encounters the rear face of the gage bar 156 when the cutter approaches the forward ends of the arms of the horse-shoe slot of the templet; and depending upon the adjustment of 100 the gage forward or rearward the limits of travel of the cutter at the ends of its horse-shoe course are regulated. Thus, for a large shoe having a long heel-seat, the cutter will start substantially from the end of the arm 105 of the templet slot containing the vestibule 107 and will continue around the slot and be arrested at the same forward position in the other arm. For a shorter heel-seat, relative adjustment between the gage on the one hand 110 and the templet and shoe holder on the other hand will be such that the cutter starts farther back in the first arm of the slot and stops at a corresponding point in the other arm. The vestibule 107 of the slot is made 115 sufficiently deep from front to rear to permit the cutter to move relatively rearward therein when the table is advanced to the position at which the housing of the cutter encounters 120 the gage.

The adjustment which has been described is made use of in such manner that a heel of the proper size corresponding to the shoe which is to be operated upon will serve to determine the nature of the adjustment. For 125 this purpose a stop 157 is carried by the left-hand block 75 to the rear of slide 135 so positioned that when a heel y (Fig. 3) of the size to be attached to the shoe to be operated on can be introduced lengthwise between the 130

abutment and the end of the slide, the slide is in proper adjustment both for the trimming and beveling cutter and for the transversely movable knife.

5 A presser-foot 158 is mounted on the inner end of the knife-bar 141, the presser foot being in advance of the cutting edge of the knife in respect to the direction of cutting movement. This presser-foot bears un-
10 yeldingly upon the top of the sole travel-
ing across it as the knife makes its cut, so as to hold the leather down against the last and insure an accurate cut. The presser-foot is also vertically adjustable on the knife-bar
15 relatively to the knife, for the purpose of regulating the depth of cut. In the particular construction illustrated the presser-foot comprises a rigid member 158, which is connected at its upper end by a hinge 159 to the
20 projecting end of a member 160, which is hinged at its inner end at 161 to a bracket 162 secured to the top of the knife-bar.

An adjustment screw 163 having a knurled operating head passes downward through an
25 enlarged hole in the member 160 into a screw-threaded bore in the bar, the head of this screw rigidly sustaining the member 160 and therefore the pressure-foot against upward movement at any adjustment, and the mem-
30 ber 160 being held up against said head by a spring 164. The hinge 159 enables the presser-foot to trail idly on the return stroke of the knife-bar and knife without exerting any substantial pressure on the work piece,
35 while on the forward stroke it is sustained rigidly in a vertical position by abutment against a projection 165 extending from the end of the knife-bar. The lower end of the presser-foot which bears upon the leather is
40 in the form of a horizontal roller 166, which extends entirely across the cutting edge of the knife and somewhat beyond the same in both directions.

Figs. 18, 19 and 20 illustrate another form
45 of interconnected mechanism for operating the table 78 and the shoe-support 53. In place of the treadle lever 73 this construction utilizes a hand lever 73^a fulcrumed in the upper part of the fixed frame. The operating arm of this lever projects from a hub
50 167, which is on the outer end of a rock-shaft 168 passing through one of the frame blocks 75, the other arm of the lever, marked 169, being fixed on the inner end of this shaft and being connected with the forward end of the table 78 by a link 170. The hub 167 has a flat portion 171 to cooperate with a sliding flat end locking bolt 172 guided in a socket
55 173 on the frame member and urged forward by a stout spring 174. An impositive lock is thus formed, which both holds the mechanism in the actuated condition without requiring the operator to keep his hand on the lever and also determines a definite forward posi-
60 tion for the table. A short arm 175 project-

ing from the hub connects with a thrust link 176, which extends downward, and at its lower end passes through an opening in the outer end of a lever 56^a, which corresponds to the lever 56, previously described, with its
70 power arm sufficiently extended for the purpose. A compression spring 74^a interposed between the lever 56^a and the collar 178 on the link 176 performs the function of the spring 74 of the previously described em-
75 bodiment.

The operation will now be briefly stated. It will be understood that the sliding table 78 is in its rearward position, seen in Fig. 3, and that the stem of the cutter is in the vestibule 107 of the horse-shoe slot 86 of the templet. By loosening the nut 119 and swinging the lever 112 the operator laterally expands or contracts the sections of the templet to the proper degree for the width of heel-seats to be operated upon and having done so locks the adjustment by tightening the nut. He also makes adjustment for the length of the heel-seat in respect to both cutting agencies by setting the slide 135 slightly forward or rearward by means of the screw 137, using a heel *y* such as is to be attached to the shoe operated upon to ascertain the proper adjustment, as has been described. Then he places a last 15 bearing one of the unfinished shoes 14 upon the last pin on top of the shoe-support or post 53, the shoe being upside down with its heel portion at the rear and its toe pointing forward. At this time the shoe-support is held tilted forward by its spring 63. Having placed the shoe on the support, the operator moves the handle 49 to open the jaws or crease plates 28 of the holder, and then thrusts the shoe-support and shoe rearwardly into the recess of the machine, bringing the heel-seat portion of the sole between the conforming blade portions 29 of the crease plates. By relieving the hand pressure on the lever 49, the crease plates are now caused to enter the crease between the feather of the sole and the turned-in portion of the upper and to grip the shoe in this manner through the action of the spring 50. Next the operator presses upon the pedal 73 or pulls forward upon the equivalent handle 73^a of the second embodiment, and thereby advances the table 78 to its definite forward position and also forces the shoe-support 53 upward through the cushioned pressure exerted through the spring transmission element 74 or 74^a. This brings the shoe-support and shoe firmly up against the holder, and the holder is rigidly sustained against any yielding by the automatic clutch 66.
110 When the table 78 is brought forward, the housing 89 of the rotary cutter strikes against the gage 156 toward the end of the forward movement, thereby restraining the cutter against any further forward move-
115 120 125 130

ment and determining the proper point along the side of the sole where the beveling should begin for the particular size of shoe. The cutter, if not already rotating, is started and the operator then grasps the handles 122 and 125 of the controlling linkage, and first moves the cutter laterally up against the side of the sole, then rearwardly, next around the rear end and finally forwardly in the path 10 determined by the templet, the trimming and beveling being completed when the cutter again strikes the gage. In this way the edge of the heel portion of the sole is trimmed off substantially to the junction between the 15 upper and sole, and the peripheral portion of the heel-seat surface of the sole is beveled, in the manner indicated. The cutter is then returned to its starting position in the templet slot and the table carrying the cutter and its 20 guiding means is returned to its rearward position. Next the attendant depresses the pedal 146, thereby forcing the knife-bar 141 transversely of the machine. This causes the knife 153 to make a scarf cut across the front 25 of the heel-seat region of the sole, in the manner which has been fully described. This accomplished, the knife-bar and knife are returned to their outward positions, out of the path of the beveled trimming cutter. The 30 work in the machine is now completed and the operator opens the crease plates 28, whereupon the spring 63 tilts the shoe-support 53 forward, carrying the shoe out of the recess of the machine to a position where it can be 35 conveniently removed. The forward rocking movement of the support 53 automatically releases the clutch 66, so as to insure lowering of the support by the spring 60. Another shoe on its last is then placed upon the post 40 of the support and the cycle of operations is repeated.

If preferred, the transversely movable knife 153 may be operated to form the heel-breast receiving cut before the peripheral portion of the heel-seat is trimmed and beveled. Obviously, the machine is capable of operating either way.

The last support and its operating means disclosed in this application are not claimed 45 herein, since they are claimed in our co-pending application, Serial No. 573,233, filed July 6, 1922, as a division of this application.

While the preferred forms of the invention have been described in detail, it will be understood that numerous changes in form, proportion, arrangement and detail may be made without departing from essentials.

What is claimed as new is:

1. A machine for operating on the heel portion of the sole of a shoe in preparation for the reception of a heel having, in combination, means for holding a shoe, a rotary bevel cutter supported with its axis perpendicular to the plane of the sole of the shoe thus held 50 for universal movement parallel with said

plane, said cutter being formed to trim off the edge of the heel portion of the sole and to bevel its heel-seat face, and means for directing said cutter to travel around the sides and back of the heel portion of the sole. 70

2. A machine for operating on the heel portion of the sole of a shoe in preparation for the reception of a heel, having, in combination, means for holding a shoe, a rotary bevel cutter supported with its axis perpendicular to the plane of the sole of the shoe thus held for universal movement parallel with said plane, said cutter being formed to trim off the edge of the heel portion of the sole and to bevel its heel-seat face, and a horse- 80 shoe slotted templet for guiding said cutter. 75

3. A machine for operating on the heel portion of the sole of a shoe in preparation for the reception of a heel, having, in combination, means for holding a shoe, a rotary bevel cutter supported with its axis perpendicular to the plane of the sole of the shoe thus held for universal movement parallel with said plane, said cutter being formed to trim off the edge of the heel portion of the 90 sole and to bevel its heel-seat face, means for rotating said cutter, and means for directing the rotating cutter to travel around the sides and back of the heel portion of the sole. 85

4. A machine for operating on the heel portion of the sole of a shoe in preparation for the reception of a heel, having, in combination, means for holding a shoe, a rotary bevel cutter supported with its axis perpendicular to the plane of the sole of the shoe 100 thus held for universal movement parallel with said plane, said cutter being formed to trim off the edge of the heel portion of the sole and to bevel its heel-seat face, and an adjustable templet for guiding said cutter. 105

5. A machine for operating on the heel portion of the sole of a shoe in preparation for the reception of a heel, having, in combination, means for holding a shoe, a rotary bevel cutter supported with its axis perpendicular to the plane of the sole of the shoe 110 thus held for universal movement parallel with said plane, said cutter being formed to trim off the edge of the heel portion of the sole and to bevel its heel-seat face, and a horse-shoe templet for guiding said cutter, comprising relatively movable sections. 115

6. In a machine of the character described, a frame, means thereon for holding a shoe, a cutter-head having a rotary cutter for trimming and beveling the edge of the sole of the shoe at the heel-seat, the axis of rotation of the cutter being perpendicular to the plane of the sole of the shoe thus held, a solid support for said cutter-head permitting universal movement thereof parallel with said plane, and a horse-shoe-slotted templet guiding the cutter-head, the stem of the cutter-head passing through the templet. 120

7. In a machine of the character described, 125

- the combination of a cutter-head having a rotary cutter for trimming and beveling the edge of a sole at the heel-seat, a disk on the cutter-head extending widely therefrom, a table formed with a flat pocket presenting upper and lower bearing faces closely receiving said disk between them, the disk and cutter-head being freely movable in all directions parallel with said faces, and means for directing the movement of the cutter-head.
8. In a machine of the character described, a frame, means thereon for holding a shoe, a cutter-head having a rotary cutter for trimming and beveling the edge of the sole of the shoe at the heel-seat, a disk on the cutter-head, a table formed with a flat pocket presenting upper and lower bearing faces closely receiving said disk between them, the disk and cutter-head being freely movable in all directions parallel with said faces, said table being slidably supported on the frame, and means movable with the table for directing the movement of the cutter-head.
9. In a machine of the character described, a frame, means thereon for holding a shoe, a cutter-head having a rotary cutter for trimming and beveling the edge of the sole of the shoe at the heel-seat, a disk on the cutter-head, a table formed with a flat pocket presenting upper and lower bearing faces closely receiving said disk between them, the disk and cutter-head being freely movable in all directions parallel with said faces, said table being slidably supported on the frame, means movable with the table for directing the movement of the cutter-head, and a templet on the table in guiding relation to the stem of the cutter-head.
10. In a machine of the character described, a frame, means thereon for holding a shoe, a rotary cutter for trimming and beveling the edge of the sole of the shoe at the heel-seat, said cutter being supported for universal two-dimensional movement, a horse-shoe-slotted templet for guiding said cutter, and means for moving the cutter comprising pivotally jointed arms, one arm connected to the cutter, and another arm having a relatively fixed pivot.
11. In a machine of the character described, a frame, means thereon for holding a shoe, a cutter-head having a rotary cutter for trimming and beveling the edge of the heel-seat of the sole of a shoe held by said means, a disk on the cutter-head, a table formed with a flat pocket presenting upper and lower bearing faces closely receiving said disk between them, the disk and cutter-head being freely movable in all directions parallel with said faces, said table being slidably supported on the frame, means movable with the table for directing the movement of the cutter-head, a templet on the table in guiding relation to the stem of the cutter-head, and means for moving the cutter comprising pivotally jointed arms, one arm connected to the cutter, and another arm having a relatively fixed pivot.
12. A machine of the character described, having a rotary cutter for trimming and beveling the edge of the sole of a shoe at the heel-seat, said cutter being supported for universal two-dimensional movement, a horse-shoe-slotted templet in guiding relation to the cutter, a forward gage cooperative with the cutter to limit the extent of working travel of the cutter in the arms of the slot, and means for relative adjustment between the gage and templet.
13. A machine of the character described, having a rotary cutter for trimming and beveling the edge of the sole of a shoe at the heel-seat, said cutter being supported with its axis perpendicular to the plane of the sole to be operated on for universal two-dimensional movement parallel with said plane, means for directing the cutter in a horse-shoe path, and a gage adjustable to limit the movement of the cutter toward the ends of the horse-shoe path.
14. In a machine of the character described, a frame, a shoe-holder thereon, a rotary cutter for trimming and beveling the edge of the sole of a shoe at the heel-seat, the axis of rotation of the cutter being perpendicular to the plane of the sole of the shoe thus held, a solid support for said cutter permitting universal horizontal movement of the cutter over the shoe-holder, a templet for guiding the cutter in a horse-shoe path, a gage adjustable to limit the movement of the cutter toward the ends of the horse-shoe path, and means for relatively adjusting said gage on the one hand and the shoe-holder and templet on the other hand.
15. A machine of the character described, having a rotary cutter for trimming and beveling the edge of the sole of a shoe at the heel-seat, said cutter being supported for universal two-dimensional movement, and a sectional horse-shoe-slotted templet guiding the cutter, said templet being expansible and contractible for different widths of heel-seats.
16. A machine of the character described, having a rotary cutter for trimming and beveling the edge of the sole of a shoe at the heel-seat, said cutter being supported for universal two-dimensional movement, a sectional horse-shoe-slotted templet guiding the cutter, said templet being expansible and contractible for different widths of heel-seats, a gage cooperative with the cutter to limit the forward extent of working travel of the cutter in the arms of the slot, and means for relatively adjusting the gage and templet according to the length of heel-seat.
17. In a machine of the character described, a templet formed of relatively movable sections having an overlapping joint and together presenting a horse-shoe-slot

- corresponding to the contour of a heel-seat and expansible and contractible for different widths of seat.
18. In a machine of the character described, the combination of a rotary bevel cutter to operate on the edge of the sole of a shoe, and a horse-shoe-slotted templet for guiding said cutter, said templet having a laterally extended vestibule at the end of one of the arms of its slot.
19. In a machine of the character described, the combination of a rotary cutter for trimming and beveling the edge of a sole at the heel-seat, said cutter being supported for universal two-dimensional movement, and a templet for guiding the cutter formed of relatively movable sections together presenting a horse-shoe slot and expansible and contractible for different widths of heel-seat, said sections having rearward extensions pivoted remotely from the slot.
20. In a machine of the character described, the combination of a rotary cutter for trimming and beveling the edge of a sole at the heel-seat, said cutter being supported for universal two-dimensional movement, a templet for guiding the cutter formed of relatively movable sections together presenting a horse-shoe slot and expansible and contractible for different widths of heel-seat, a lever connected with the sections to effect equal movement thereof, and means for locking the sections in adjustment.
21. A machine of the character described, having a cutter-head including a rotary cutter for trimming and beveling the edge of a sole at the heel seat and a presser foot encircling the cutter, a solid support permitting universal movement of the cutter in a plane and preventing displacement in either direction from said plane, and means for directing the movement of the cutter-head.
22. A machine of the character described comprising a frame, a rotary cutter supported on the frame for universal two-dimensional movement to trim and bevel the sole of a shoe at the heel-seat, means for directing the movement of said cutter, a transversely-guided knife and means for operating the same, and a holder on the frame for holding the shoe in a fixed position for the action of said cutter and knife.
23. A machine of the character described comprising a frame, a rotary cutter supported on the frame for universal two dimensional movement to trim and bevel the sole of a shoe at the heel-seat, means for directing the movement of said cutter, a knife-bar guided in the frame for rectilinear transverse movement, a knife on the inner end of said knife-bar, means for reciprocating said knife-bar to carry the knife across the front of the heel-seat and back away from the path of the rotary cutter, and a holder on the frame for holding the shoe in a fixed position for the action of said cutter and knife.
24. A machine of the character described comprising a frame, a rotary cutter supported on the frame for universal two-dimensional movement to trim and bevel a sole at the heel-seat, means for directing the movement of said cutter, a transversely-guided knife and means for operating the same, and adjusting means common to said cutter and knife for different lengths of heel-seat.
25. A machine of the character described comprising a frame, a rotary cutter supported on the frame for universal two-dimensional movement to trim and bevel the sole of a shoe at the heel-seat, means for directing the movement of said cutter, a transversely-guided knife and means for operating the same, a holder on the frame for holding the shoe in a fixed position for the action of said cutter and knife, and adjusting means common to said cutter and knife for different lengths of heel-seat.
26. A machine of the character described comprising a frame, a rotary cutter supported on the frame for universal two-dimensional movement to trim and bevel a sole at the heel-seat, means for directing the movement of said cutter, a transversely-guided knife and means for operating the same, a forward gage for said cutter, and means for effecting forward and rearward adjustment of said gage and the knife conjointly.
27. A machine of the character described comprising a frame, a rotary cutter supported on the frame for universal two-dimensional movement to trim and bevel the sole of a shoe at the heel-seat, means for directing the movement of said cutter, a transversely-guided knife and means for operating the same, a holder on the frame for holding the shoe in a fixed position for the action of said cutter and knife, a forward gage for said rotary cutter, and a single means for effecting forward and rearward adjustment between said gage and knife on the one hand and the shoe-holder on the other hand.
28. A machine of the character described comprising a frame, a rotary cutter supported on the frame for universal two-dimensional movement to trim and bevel the sole of a shoe at the heel-seat, a templet for guiding said cutter, a transversely guided knife and means for operating the same, a holder on the frame for holding the shoe in a fixed position for the action of said cutter and knife, a forward gage for said rotary cutter, and a single means for effecting forward and rearward adjustment between said gage and knife on the one hand and the templet and shoe-holder on the other.
29. In a machine of the character described, a frame, a holder thereon for a shoe, a table movable forwardly and rearwardly

on the frame, a rotary bevel cutter supported on said table for universal movement parallel therewith, means on the table for guiding said cutter to travel around the sides 5 and rear of the heel-seat of the sole of the shoe, a knife transversely guided in a relatively stationary part of the frame, means for adjusting the knife forwardly and rearwardly, and a forward gage for the rotary cutter connected with the knife for adjustment therewith.

30. In a machine of the character described, the combination of a frame, a rotary cutter for trimming and beveling the edge 15 of the heel-seat of a shoe, a support for said cutter permitting universal movement thereof in a plane, means for guiding said cutter, a transversely movable knife-bar carrying a knife, a slide in which said knife-bar is 20 guided, said slide being adjustable forwardly and rearwardly on the frame, and a forward gage for the rotary cutter also carried by said slide.

31. A machine of the character described, 25 comprising a frame, means thereon for holding a shoe and presenting the heel-seat portion of its sole, a knife constructed and arranged to make a transverse forwardly dipping cut extending across and partway 30 through the sole at the front of said heel-seat portion, and means for operating the knife.

32. In a machine of the character described, a frame, means thereon for holding 35 a shoe and presenting the heel-seat region of its sole, a knife guided on the frame for transverse movement across the front of the heel-seat region of the sole of the shoe thus held to cut a tongue, and means for operating the knife.

33. In a machine of the character described, a frame, means thereon for holding a shoe and presenting the heel-seat region of its sole, a knife-bar guided in the frame for 45 movement transversely of the sole of the shoe thus held, a knife mounted on said bar to cut transversely across the front of the heel-seat, said knife being dipped forwardly of the sole and transversely of its path of movement, and means for reciprocating the knife-bar.

34. In a machine of the character described, a frame, means thereon for holding a shoe and presenting the heel-seat region 55 of its sole, a knife-bar guided in the frame for movement transversely of the sole of the shoe thus held, a knife mounted on said bar to cut across the front of the heel-seat, said knife being dipped forwardly of the sole and 60 transversely of its path of movement, a presser-foot mounted on the knife-bar in front of the knife in respect to its cutting stroke, a vertical adjustment for said presser-foot to regulate the depth of cut, and means 65 for reciprocating the knife-bar.

35. A heel-seat fitting machine having, in combination, a knife bar mounted for endwise movement, a knife rigidly secured to one end of the knife bar for movement in a fixed path, and a presser foot in front of the knife hinged 70 to the end of the knife bar and arranged for operative engagement with the work during the cutting stroke of the knife and knife bar and to trail idly over the work during the return stroke of the knife and knife bar without exerting any substantial pressure on the work.

36. In a machine of the character described, the combination of an endwise movable knife bar, a knife carried thereby, a vertically adjustable member carried by the knife bar, and a presser foot in front of the knife hinged 80 to said member and arranged to bear against the work on the cutting stroke of the knife and knife bar and to trail idly on the return 85 stroke.

37. In a machine of the character described, the combination of an endwise movable knife bar, a knife secured thereto, and a presser foot hinged to the knife bar and comprising 90 a work-engaging roll arranged unyieldingly to engage the work substantially in front of the knife on the cutting stroke of the knife and knife bar and to trail idly on the return 95 stroke without exerting any substantial pressure on the work.

38. In a machine of the character described, a frame, a raisable and lowerable shoe-support thereon, a shoe-holder on the frame above the shoe-support, a table 100 slideable on the frame forwardly and rearwardly above the shoe-holder, a rotary cutter supported on the table for universal movement parallel therewith, means for directing the cutter, a common operating lever, and connections from said lever to the shoe-support and 105 slideable table for operating both of them.

39. In a machine of the character described, a frame, a raisable and lowerable shoe-support thereon, a shoe-holder on the frame above the shoe-support, a table 110 slideable on the frame forwardly and rearwardly above the shoe-holder, a rotary cutter supported on the table for universal movement parallel therewith, means for directing the cutter, a common operating lever, and connections from said lever to the shoe-support and 115 slideable table for operating both of them, the connections to the shoe-support for raising the same including a yielding spring transmission element.

40. In a machine of the character described, a frame, a raisable and lowerable shoe-support thereon, a shoe-holder on the frame above the shoe-support, a table 120 slideable on the frame forwardly and rearwardly above the shoe-holder, a rotary cutter supported on the table for universal movement parallel therewith, means for directing the cutter, a common operating mechanism having 125

ing branches for raising the shoe-support and advancing the table respectively, and a lock for holding said mechanism in definite actuated position.

- 5 41. In a machine of the character described, a frame, a raisable and lowerable shoe-support thereon, a shoe-holder on the frame above the shoe-support, a table slidable on the frame forwardly and rearwardly 10 above the shoe-holder, a rotary cutter supported on the table for universal movement parallel therewith, means for directing the cutter, a common operating mechanism having branches for raising the shoe-support 15 and advancing the table respectively, the branch for raising the shoe-support including a yielding spring transmission element, and a lock for holding said mechanism in definite actuated position.
- 20 42. In a machine of the character described, a frame, a raisable and lowerable shoe-support thereon, a shoe-holder on the frame above the shoe-support, a table slidable on the frame forwardly and rearwardly 25 above the shoe-holder, a rotary cutter supported on the table for universal movement parallel therewith, means for directing the cutter, a hand lever on the frame, connections from said lever to the table for drawing the 30 same forward, a lower lever on the frame, and a spring-yielding connection extending from the hand-lever to said lower lever, said lower lever being arranged to elevate the shoe-support.
- 35 43. In a machine of the character described, a frame, a rotary cutter for trimming and beveling the edge of the heel-seat region of the sole of a shoe, a slidable table by which said cutter is supported for universal movement parallel with the table, means for directing the cutter, an operating lever connected with said table, a hub connected to said operating lever and having a flat portion, and a spring-pressed impositive locking bolt 40 cooperative with said hub.

44. In a machine of the character described, a frame, a table slidable thereon, a rotary cutter supported by said table for universal movement parallel therewith, means 50 carried by the table for directing the cutter, an operating lever and connections for advancing the table, a spring for restoring the same, and a lock for holding the table in advanced position.

- 55 45. In a heel-seat fitting machine, in combination, means including a rotary trimming cutter, a positioning device to limit the movement thereof, a measuring device to determine the size of the attaching surface of the heel to be attached to the shoe operated on, and a connection from the measuring device to the positioning device to control the operation of the rotary trimming cutter to fit the shoe to the particular heel so measured.
- 60 46. In a heel-seat fitting machine, in combi-

nation, a trimming device arranged for movement peripherally of the heel-seat of a sole and a sole-positioning device cooperating to position a sole for the action of the trimming device thereon, a gage movable to measure the heel to be fastened upon the particular sole being operated upon, and means operated by the gage in its movements to limit the movement of the trimming device to cause it to fit the sole according to the heel so measured. 75

47. A machine for use in making shoes comprising, in combination, a knife, means for moving the knife transversely of a shoe to make a cut across the sole of the shoe at the heel-breast line, a support to present the work thereto, and means spaced therefrom engaging a separate templet to vary the relative position of the knife and the support to determine the heel-breast line according to the templet. 80

48. A heel seat fitting machine comprising, in combination, shoe supporting and positioning members, a cutter movable peripherally from breast corner to breast corner of the sole of a shoe supported by said members to fit it for the attachment of a wood heel, a mechanically-operated knife to form a shoulder at the heel breast line of the sole of said shoe, a device for limiting the extent of the part of the sole operated on by said cutter and for varying the relative positions of the shoe and said knife to determine the position of the heel breast line, and mechanism for engaging a heel and measuring the length of its seat surface and for setting said device according to the length so measured in order to adjust the machine to trim different shoes differently to fit them for the attachment of different heels measured by said mechanism. 95

49. A machine for use in the manufacture of shoes having, in combination, a knife, means for moving the knife transversely across the sole of the shoe to make a cut in the shoe at the heel breast line, a gage member movable into engagement with a heel such as is to be attached to the shoe, and means controlled by the position of the gage member arranged to control the relative position of the shoe and the knife to locate the cut in accordance with the length of the heel to be attached to the shoe. 105

50. A heel-seat fitting machine having, in combination, means for holding a shoe to be operated upon, a knife movable transversely across the sole of a shoe held stationary by said means and arranged to cut the sole to prepare the sole for the reception of the breast of a heel, a gage arranged to measure a heel such as is to be attached to the shoe to be operated upon, and means controlled by the position of the gage to cause the operation of the knife to be controlled by a dimension of the heel. 115

51. A heel-seat fitting machine having, in combination, a rotary cutter, means for op- 120

- 65 46. In a heel-seat fitting machine, in combination, a rotary cutter, means for op- 125

erating said cutter to trim surplus material from the peripheral portion of the heel-seat of the sole of a shoe, and means arranged to engage opposite ends of a heel such as is to be attached to the shoe and to control the forward extent of the trimming operation of the cutter upon the shoe in accordance with the length of the heel.

52. A heel-seat fitting machine having, in combination, means for holding a shoe in a stationary position, a cutter, means for moving said cutter peripherally of the heel-seat of the sole of a shoe thus held to trim surplus material from the peripheral portion of the heel-seat portion of the sole, means arranged to engage opposite surfaces of a heel such as is to be attached to the shoe, and mechanism connected to said means to control the dimensions to which the heel-seat of the sole is trimmed.

53. A heel-seat fitting machine having, in combination, a shoe support, a knife arranged for movement transversely of said support and across the tread surface of the sole of a shoe on the support to prepare the sole of the shoe for the reception of the breast of a heel, a fixed and a movable gage member arranged for engagement with opposite ends of a heel such as is to be attached to the shoe, and means controlled by the position of the movable gage member arranged to control the relative position of the shoe and the knife to locate the cut in accordance with the length of the heel to be attached to the shoe.

35 54. A heel-seat fitting machine having, in combination, a guide shaped to conform substantially to the contour of the heel-seat of a sole and spaced from the heel-seat portion of the sole to be operated on, a beveling cutter, and means to move the cutter under the control of the guide to trim surplus material from and to bevel the peripheral portion of the heel-seat of a sole.

45 55. A heel-seat fitting machine having, in combination, a guide spaced from the heel-seat portion of the sole to be operated on, a beveling cutter, and means to move the cutter peripherally of the heel-seat of a sole under the control of the guide to trim surplus material from and to bevel the peripheral portion of the heel-seat.

55 56. A heel-seat fitting machine having, in combination, a guide shaped to conform substantially to the contour of the heel-seat of the sole of a shoe and spaced from the heel-seat portion of the sole to be operated on, a beveling cutter, and lever mechanism operable to move the cutter under the control of the guide to trim surplus material from and to bevel the peripheral portion of the heel-seat of the sole of a shoe.

60 57. A heel-seat fitting machine having, in combination, a work support, a plurality of flat crease plates movable toward and from a

shoe carried by said support and having thin edges arranged to enter the rand crease of the shoe, a guide adjustable to conform to the periphery of the heel-seat of the shoe thus supported, and a beveling cutter movable under the control of said guide to trim surplus material from and to bevel the peripheral portion of the heel-seat of the shoe thus supported.

58. A heel-seat fitting machine having, in combination, a work support, a pair of crease plates arranged to enter the rand crease of a shoe carried by said support and movable about a point substantially in line with the back seam of said shoe, a guide adjustable to conform to the periphery of the heel-seat of the shoe thus supported, and a cutter movable under the control of said guide to trim surplus material from the peripheral portion of the heel-seat of the shoe thus supported.

59. A heel-seat fitting machine having, in combination, a shoe holder having a thin edge arranged to support the edge of the heel-seat portion of the sole of a shoe, an approximately horseshoe-shaped guide, and a cutter movable under the control of said guide to trim surplus material from the peripheral portion of the heel-seat of the sole of a shoe thus held.

60. A machine of the class described having, in combination, a plurality of relatively movable flat plates, an approximately horseshoe-shaped guide surface formed on said plates, and means for adjusting said plates to vary the spread of said guide surface.

61. A heel-seat fitting machine having, in combination, a plurality of relatively movable flat plates, an approximately horseshoe-shaped guide surface formed on said plates, means for adjusting said plates to vary the spread of said guide surface, and a cutter mounted for movement under the control of said guide surface to trim surplus material from the peripheral portions of the heel-seats of soles.

62. A heel-seat fitting machine having, in combination, a pair of flat plates mounted for pivotal movement, an approximately horseshoe-shaped guide surface formed on said plates, means for adjusting said plates toward and from each other about the pivotal mountings to vary the spread of said guide surface, and a cutter mounted for movement under the control of said guide plates to trim surplus material from the peripheral portions of the heel-seats of soles.

63. A heel-seat fitting machine having, in combination, a guide shaped to conform substantially to the contour of the heel-seat of a sole, a cutter, means to move the cutter peripherally of the heel-seat of a sole under the control of the guide to trim surplus material from the heel-seat of the sole, and means to vary the spread of the path of movement

of the cutter in accordance with the dimensions to which the heel-seat of the sole is to be trimmed.

64. A heel-seat fitting machine having, in combination, a support for a shoe, an approximately horseshoe-shaped guide spaced from the heel-seat portion of the sole of a shoe on the support, and a cutter arranged for movement peripherally of the heel seat of the sole of a shoe on the support under the control of said guide to trim surplus material from and to bevel the peripheral portion of the heel-seat of the sole.

65. A heel-seat fitting machine having, in combination, an approximately horseshoe-shaped guide, and a rotary cutter arranged for movement under the control of said guide to trim surplus material from the peripheral portion of the heel-seat of the sole of a shoe.

66. A heel-seat fitting machine having, in combination, guiding means comprising a pair of relatively movable sections, an approximately horseshoe-shaped guide surface formed on said sections; and a cutter mounted for movement peripherally of the heel-seat of a sole under the control of said guide surface to trim surplus material from the peripheral portion of the heel-seat of the sole.

67. A heel-seat fitting machine having, in combination, a work holder comprising a pair of crease plates adjustable about a point substantially in line with the back seam of a shoe held thereby, and a cutter for trimming surplus material from the peripheral portion of the heel-seat of the sole of a shoe thus held.

68. A heel-seat fitting machine having, in combination, guiding means comprising a pair of relatively movable sections, an approximately horseshoe-shaped guide surface formed on said sections, means arranged to enter the rand crease of a shoe to support the peripheral portion of the heel-seat of the sole of a shoe, and a cutter mounted for movement peripherally of the heel-seat of the sole of a shoe under the control of said guide surface to trim surplus material from the peripheral portion of the heel-seat of the sole of said shoe.

69. A heel-seat fitting machine having, in combination, a holder comprising a plurality of crease plates arranged to enter the rand crease of a shoe, and a knife movable transversely clear across the sole of said shoe from one edge to the other to prepare the sole to receive the breast of a heel.

70. A heel-seat fitting machine having, in combination, a work support, and a knife arranged to operate upon the heel-seat portion of the sole of a shoe carried by said support and movable transversely of the sole of said shoe clear across the sole of said shoe from one edge to the other.

71. A heel-seat fitting machine having, in combination, a plurality of crease plates ar-

ranged to enter the rand crease of a shoe, a knife arranged to operate upon the heel-seat portion of the sole of the shoe, and means for moving said knife transversely across the seat of the sole of said shoe clear across the sole from one edge to the other.

72. A heel-seat fitting machine having, in combination, a holder comprising a plurality of crease plates arranged to enter the rand crease of a shoe, a knife having a cutting edge inclined relatively to the surface of the sole of the shoe, and means for moving the knife transversely across the sole of the shoe to prepare the sole to receive the breast of a heel.

73. A heel-seat fitting machine having, in combination, a shoe holder comprising a pair of crease plates arranged for pivotal movement about a point substantially in line with the back seam of a shoe to cause the plates to enter the rand crease of a shoe and hold the shoe while it is operated upon, a knife, and means for moving the knife transversely of the sole of the shoe to prepare the sole to receive the breast of the heel.

74. A heel-seat fitting machine having, in combination, a shoe holder comprising a plurality of crease plates arranged to enter the rand crease of a shoe to hold the shoe while it is operated upon, a knife having a cutting edge inclined at a small angle to the sole of the shoe, and means to move the knife relatively to the shoe to cause the knife to cut the sole of the shoe to prepare the sole for the reception of a heel.

75. A heel-seat fitting machine having, in combination, a shoe holder comprising a pair of crease plates arranged for pivotal movement about a point substantially in line with the back seam of a shoe to cause the plates to enter the rand crease of a shoe to hold the shoe while it is operated upon, a knife having a cutting edge inclined relatively to the surface of the sole of the shoe, and means to move the knife relatively to the shoe to cause the knife to cut the sole of the shoe to prepare the sole for the reception of a heel.

76. A heel-seat fitting machine having, in combination, a shoe holder comprising a plurality of crease plates arranged to enter the rand crease of a shoe to hold the shoe while it is operated upon, a knife having a cutting edge inclined relatively to the sole of the shoe, and means for moving the knife transversely across the sole of the shoe, thereby making a transverse cut inclined lengthwise of the sole of the shoe.

77. A heel-seat fitting machine having, in combination, a shoe holder comprising a plurality of crease plates arranged for pivotal movement about a point substantially in line with the back seam of a shoe to cause the plates to enter the rand crease of the shoe and hold the shoe while it is operated upon, a knife having a cutting edge inclined rela-

- tively to the sole of the shoe, and means for moving the knife transversely of the sole of the shoe, thereby making a transverse cut inclined lengthwise of the sole of the shoe.
- 5 78. A heel-seat fitting machine having a work holder comprising a pair of crease plates adjustable about a point substantially in line with the back seam of a shoe held thereby, and means for making a heel-breast 10 receiving cut in the sole of a shoe thus held.
79. A heel-seat fitting machine having, in combination, a frame, a shoe support arranged to be raised and lowered therein, a shoe holder carried by the frame about the 15 shoe support, a table slidable in the frame forwardly and rearwardly above the shoe holder, a cutter carried by the table for movement in a direction parallel thereto, means for guiding the cutter to trim surplus material from the peripheral portion of the heel-seat of the sole of a shoe carried by the shoe support and shoe holder, and common operating means for the shoe support and sliding table.
- 20 80. A machine for operating upon shoes having, in combination, a support comprising a pair of parallel plates each provided with an opening, a third plate positioned between the parallel plates and guided by said plates for universal movement in a plane parallel to said plates, a shaft carried by said movable plate and projecting through the openings in the parallel plates, and a tool carried by said shaft.
- 25 81. A machine for operating upon shoes having, in combination, a plate, an operating tool carried by said plate, and a support for said plate provided with a pair of parallel portions between which the plate is located 30 for universal movement in a plane parallel to said parallel portions, the parallel portions of said support being provided with aligning openings to accommodate said tool during relative movement of said plate and 35 said support.
82. In a machine of the character described, a shoe holder comprising relatively movable jaws having thin edges formed to enter the rand crease of a shoe between the 40 extension of the outsole and the upper to support the edge of the sole around the heel-seat and to engage and support the upper adjacent to the rand crease, means positioned below the jaws constructed and arranged to 45 support the shoe, means for urging the support and shoe yeldingly against the jaws, and means for clamping said support in any position to which it may have been moved.
- 50 83. In a machine of the character described, a shoe-holder comprising a plurality of relatively movable jaw members having thin edge parts shaped to conform substantially to the sides and back of the heel portion of a shoe 55 and to enter the rand crease and engage the 60 outsole and the upper of a shoe to which the sole has been permanently attached, said jaws having substantially flat surfaces in the plane of the rand crease of a shoe carried thereby, and means for swinging said jaw members about an axis substantially in line with the 65 back seam of a shoe engaged thereby.
- 70 84. In a machine of the character described, a shoe-holder comprising relatively movable jaw members having thin edge parts formed to conform substantially to the sides and back 75 of a shoe at the heel region and to enter the rand crease between the extension of the outsole and the upper, said jaw members being segmental, and a bed-plate recessed to admit the shoe, said bed-plate having a depression 80 outside of said recess to form a circular bearing in which said jaw members are received for opening and closing movement.
85. In a machine of the character described, a bed-plate recessed to admit a shoe, said bed-plate having a circular depression whose side and bottom faces act as a bearing on said bed-plate surrounding the recess, segmental jaw 85 members complemental to said depression and movable in opposite directions in said bearing to grip and release the shoe, retaining means having a tongue and groove connection with said jaw members arranged to hold the jaw members in the depression in engagement with the bearing surfaces therein, and means for operating said jaw members.
- 90 86. In a machine of the character described, a bed-plate recessed to admit a shoe, said bed-plate being provided with a depression outside 100 of said recess to form a circular bearing, segmental jaw members having a portion of their peripheries shaped complementally to said bearing and movable in opposite directions therein to grip and release the shoe, diverging links connected to the jaw members, 105 and means for acting upon said links.
87. In a machine of the character described, a bed-plate recessed to accommodate a shoe, a circular bearing on said bed-plate about the 110 recess, segmental jaw members movable in opposite directions in said bearing to grip and release the shoe, said jaw members having circularly curved recesses at their outer upper portions, and a curved retainer superposed on and engaging in these recessed regions.
- 115 88. In a machine of the character described, a shoe holder comprising an arcuate track, a pair of relatively movable jaws formed to enter the rand crease between the extension of the outsole and the upper adjacent to the heel of the shoe and mounted in said track for pivotal movement about its center, and a shoe supporting post constructed and arranged for 120 movement from a position near the operator where a shoe may be readily removed and another shoe be placed on the post to a position.

tion in which the shoe is engaged and positioned by said movable jaws with its back seam in line with the center of said track.

89. In a machine of the character described, a shoe holder comprising a plurality of relatively movable jaws formed to enter the rand crease between the sole and the upper of a shoe and arranged to support the edge of the sole, a shoe support constructed and arranged to present the shoe with its sole uppermost for movement from a position adjacent to the operator to a position where the shoe is engaged and positioned by said jaws, and means for opening and closing said jaws and for raising and lowering said shoe support.

90. In a machine for operating upon shoes, a frame, a work support arranged for vertical adjustment with respect thereto, means for clamping the work support in any position of vertical adjustment, jaw members con-

structed and arranged to enter the rand crease of the shoe to support the same against movement in a vertical direction, and resilient means for moving said work support vertically to bring the shoe firmly into engagement with said jaw members, thereby to present and clamp the work for an operation upon the heel-seat of the shoe.

91. A machine for use in the manufacture of shoes having a work support arranged to carry a shoe the rear portion of the sole of which is to be trimmed, a continuously rotated cutter arranged for engagement with the rear portion of the sole of the shoe, and means for oscillating the cutter in a path extending substantially transversely of the sole of the shoe to cause the cutter to trim surplus stock from the rear end of the sole of the shoe.

JOHN L. PREO.

ISABELLE HENNE.
